UNITED STATES PATENT OFFICE.

JAMES G. BLUNT, OF SCHENECTADY, NEW YORK.

LOCOMOTIVE-JOURNAL-BOX CELLAR.

Application filed August 28, 1926. Serial No. 132,051.

My invention relates to lubricant cellars for locomotive journal boxes, and its object is to provide a cellar of simple, substantial, and inexpensive construction, which will embody a receptacle for fluid lubricant, and saturated waste, or other packing; which can be manufactured, exclusive of its cover and springs, as an integral casting; which can be removed from, or installed in, the journal box, as a unit; and which permits the operator to expeditiously remove worn packing, and insert a supply of new packing, without the necessity of removing the cellar from the journal box.

The invention is particularly advantageous in locomotives making long runs, where replacement of journal packing, and replenishment of lubricant, is required at intermediate stops, and insufficient time is available for complete removal and repacking of the cellars.

The improvement claimed is hereinafter fully set forth:

In the accompanying drawings: Figure 1 is a view, in elevation, of the inner face of a journal box, illustrating the application of the improved cellar thereto; Fig. 2, a section of the construction shown in Fig. 1, taken on a horizontal plane, central of the axle; Fig. 3, a section of the construction shown in Fig. 1, taken on a vertical plane, central of the axle; Fig. 4, a perspective view of the front end of the cellar; Fig. 5, a perspective view of the hinged cover; Fig. 6, a section taken on the line *a a* of Fig. 1, showing details of the cover and spring; Fig. 7, a view of the inner face of the journal box, having the improved cellar applied thereto, the journal box being recessed to receive the enlarged front end of the cellar; Fig. 8, a sectional plan view of the construction shown in Fig. 7; and, Fig. 9, a side view of the construction shown in Fig. 7.

In the practice of the invention, referring descriptively to the specific embodiment thereof which is herein exemplified, as applied in connection with a locomotive axle journal box, 10, of ordinary construction, fitted in pedestal jaws of a locomotive; I provide a lubricant cellar, indicated, as a unitary member, by the reference letter A, which is adapted to fit between the legs of the journal box, 10, and is of substantially rectangular section, the body of the cellar comprising a bottom wall, 12, two vertical side walls, 13, a vertical rear wall, 14, and a front wall, 15,

which slopes upwardly from the bottom wall to a height just sufficient to clear the underside of the axle. All of the walls are integrally united together, and it is within the contemplation of the invention, to form the body as an integral casting.

By reference to Figs. 3, 4 and 6, it will be apparent that the walls provide a receptacle or well, B, of sufficient depth to hold a suitable quantity of packing, and to store an adequate supply of fluid lubricant.

The front ends of the two side walls, 13, are flared outwardly to provide openings on each side of the axle, of sufficient size to permit the operator to readily remove used packing, and insert a new supply of packing and lubricant.

To exclude the entrance of dust and dirt into the cellar, there are provided two triangular shaped top walls, 17, which extend horizontally inward from the flared front ends of the side walls.

For securing the cellar to the journal box, there are integrally formed, on the under face of the bottom wall, one on each side thereof, lugs, 18, having eyes, 19. The legs of the journal box are each provided with lugs, 20, having eyes, which align with the eyes, 19, of the lugs, 18, and a pin, 21, passing through the respective eyes, serves to removably secure the cellar to the journal box.

The upper part of the front of the cellar, is closed by a hinged cover, 22. For securing the cover, the front wall, 15, of the body of the cellar, if formed, at each side, with a hinge knuckle, 23, having an eye, 24. The cover, 22, is provided, on its front face, near each end thereof, with a pair of parallel, vertical, outstanding ribs, 25, which terminate, at their lower ends, in hinge knuckles, 26, adapted to straddle the knuckles, 23, on the front wall, 15. Eyes, 27, are provided in the knuckles, 25, and a hinge pin, 28, passes through the eyes of the respective knuckles, hingedly securing the cover to the body.

Each pair of ribs, 25, forms a housing and guideway for one of the springs, 29, which act to hold the cover yieldingly closed, and in a substantially horizontal position when open. Disposed between the ribs of each pair, are two openings, 30 and 31, the opening, 30, being arranged near the top of the cover, and the opening, 31, at the bottom thereof. The portion of the cover intermediate the two openings is curved inwardly, to provide an abutment, 32, against which the spring, 29, bears. The springs, 29, are substantially L

shape, having a lower leg, that extends through the lower opening, 31, in the cover, and an upper leg, bent at substantially a right angle to the lower leg. The upper leg 5 extends through the upper opening, 30, in the cover, and has a bent up portion, that engages the cover, locking the spring in place. The point where the two legs of the spring join, bears against the abutment, 32.

10 The knuckles, 23, on the front wall, are each formed with two cam faces, 33 and 34. It will be apparent, by referring to Fig. 6, that when the cover is closed, the lower legs of the springs will bear against the cam faces, 33, holding the cover yieldingly shut, and that when the cover is open, the lower legs will bear against the cam faces, 34, maintaining the cover in a substantially horizontal open position.

15 20 The ribs, 25, of each pair, are joined at the top by a cross piece, 35, on which is formed an upwardly extending hook or handle, 26, by which the cover may be readily pulled open.

25 30 When it is desired to limit the amount of projection of the cellar beyond the journal box, the modified construction shown in Figs. 7, 8 and 9 may be employed. In this construction, the legs of the journal box are provided with outwardly flaring recesses, 37, which receive the flared outer ends of the side walls of the cellar.

35 My invention provides a lubricant cellar, having a receptacle or well, adapted to carry an adequate quantity of fluid lubricant, and packing; and which enables the operator to expeditiously remove used packing and insert a supply of new packing without the necessity of removing the cellar from the 40 journal box. Further, the improved construction permits the removal of the cellar from the journal box, as a complete unit, whenever occasion requires.

45 I claim as my invention and desire to secure by Letters Patent:

50 1. A lubricant cellar for locomotives, comprising a front, a rear, and a bottom wall, and two side walls, the front wall terminating below the side walls, and the side walls being outwardly flared, to provide an opening for the insertion and removal of packing, the walls constituting a receptacle for fluid lubricant and packing.

2. A lubricant cellar for locomotives, comprising an integral casting, having a front, 55 a rear, and a bottom wall, and two side walls, the front wall terminating below the side walls, and the side walls being outwardly flared, to provide an opening for the insertion and removal of packing, the walls constituting a receptacle for fluid lubricant and packing.

3. A lubricant cellar for locomotives, comprising a body, having a front, a rear, and a bottom wall, and two side walls, the front 65 wall terminating below the side walls and the side walls being outwardly flared to provide an opening for the insertion and removal of packing, the walls constituting a receptacle for fluid lubricant and packing; and a 70 cover hinged to the body for closing the opening above the front wall.

4. A lubricant cellar for locomotives, comprising an integral casting, having a front, a rear, and a bottom wall, and two side walls, the front wall terminating below the side walls, and the side walls being outwardly flared to provide an opening for the insertion 75 and removal of packing, the walls constituting a receptacle for fluid lubricant and packing, and a cover, hinged to the casting, for closing the opening above the front wall.

5. The combination of a journal box, having a recess in each of its legs; and a lubricant cellar, having side walls flared at the 80 front end, and being fitted in the recesses in the journal box legs.

6. The combination of a journal box, having an inwardly tapering recess in each of its legs; and a lubricant cellar, having flared 85 side walls, fitted in the tapered recesses in the journal box legs.

7. In a locomotive, the combination of a pair of pedestal jaws, each provided on its inner face with a tapered recess adapted to receive a flared portion of a lubricant cellar; a lubricant cellar fitted between said pedestal jaws, said cellar having a front, a rear, and a bottom wall, and two side walls, each side wall having an outwardly flared portion at one end, to provide increased space for the insertion and removal of packing, the said flared portions being fitted in the recesses in the pedestal jaws.

JAMES G. BLUNT.
